UNITED STATES PATENT OFFICE.

JOHN C. BRINK, OF MIDDLETOWN, NEW YORK.

RAILWAY-SWITCH APPARATUS.

1,188,724.

Specification of Letters Patent. Patented June 27, 1916.

Application filed December 31, 1915. Serial No. 69,552.

To all whom it may concern:

Be it known that I, JOHN C. BRINK, a citizen of the United States, and residing at Middletown, in the county of Orange and State of New York, have invented certain new and useful Improvements in Railway-Switch Apparatus, of which the following is a specification, such as will enable those skilled in the art to which it appertains to make and use the same.

This invention relates to switch apparatus for railways, and the object thereof is to provide an improved apparatus of this class which is simple in construction and positive in operation, and the construction of which involves two separate lock members, one on each side of the track and which are alternately operated in opening and closing the switch, and by means of which the switch is positively locked both in the open and closed position, and with this and other objects in view the invention consists in an apparatus of the class specified, constructed and operating as hereinafter described and claimed.

The invention is fully disclosed in the following specification, of which the accompanying drawing forms a part, in which the separate parts of my improvement are designated by suitable reference characters in each of the views, and in which:—

Figure 1 is a plan view of my improved railway switch apparatus and showing the switch closed; Fig. 2 a sectional plan view 25 but showing the switch open; and, Fig. 3 a cross section on the line 3—3 of Fig. 2.

In the drawing forming part of this specification, I have shown at *a* the main rails of a railway track and at *b* a switch rail of a switch but the part *b*² of one of the rails *b*, in the form of construction shown, also serves as one of the main rails, one rail *b* being provided with a switch tongue *b*³, and one rail *a* being provided with a switch tongue *a*², said switch tongues being hinged to their respective rails at *b*⁴ and *a*³ as shown.

The switch tongues *b*³ and *a*² are connected near their free ends by a transverse bar *c* which passes under the rails *a* and *b*—*b*², this connection being made by means of plates *c*² secured to the switch tongues and link members *c*³ pivoted to the bar *c* and to the plates *c*².

At each side of the track and on the outer side of the rails thereof are placed parallel lock boxes *d* which, in the construction

shown are opened and secured to base-boards or other supports *e*, and connected with the opposite ends of the bar *c* are lock links *f* which are movable transversely through the boxes *d*, and the lock links *f* are connected with the ends of the bar *c* by bolts *g* having forked heads *g*² in which the ends of the bar *c* fit, and said forked heads *g*² are pivoted to the ends of said bar at *g*³, and the bolts *g*, in the construction shown, are screwed into the corresponding ends of the lock links *f*.

The lock links *f* are provided with central longitudinal slots *f*² in the outer ends of which are placed anti-friction rollers *f*³, and the lock boxes *d* are provided in their opposite side walls with grooves *d*² in the same plane as the slots *f*² in the lock links *f*.

Mounted in corresponding ends of the lock boxes *d* are lock plates *h*, the outer corner portions of the inner ends of which are beveled inwardly, as clearly shown, and the lock plates *h* are movable longitudinally through the lock boxes *d* and through the lock links *f*.

Connected with the outer ends of the lock plates *h* are link bars *i* having yoke-shaped heads *i*², one of which is connected, in each instance, with the corresponding lock plate *h*, and the other end of the link bars *i* are connected with bell cranks *j* pivoted at *j*² to the base-boards *e* and also to metal clips *j*³ secured to said base-boards, and extending transversely of the track, under the rails, and under the switch tongues, is a rod *k*, the ends of which are pivoted to the bell cranks *j* at *k*².

In the construction shown an operating lever *m* is pivoted to a support *m*² at one side of the track as shown at *m*³ and a rod *n* is connected with said lever at *n*² and with one of the bell cranks *j* at *n*³.

When the switch is closed, as shown in Fig. 1, one of the lock plates *h* is in operation and the other is out of operation, but when the switch is open, as shown in Fig. 2, this position of the lock plates is reversed, and the lock plate which is in operation when the switch is closed, as shown in Fig. 1, is out of operation when the switch is open as shown in Fig. 2. It will also be observed that with the parts in the position shown in Fig. 1 in which the lock plate *h* at the right is in operation and the switch is closed, if the lever be operated, the lock plate *h* to the right will be drawn out of operation, and the lock plate *h* at the left will be thrown into operation, and in this operation of said

lever, and of the lock plates, the bar *c* is moved to the left and carries with it the switch tongues *b*³ and *a*², and the switch is opened as shown in Fig. 2, and in order to close the switch again, all that is necessary is to move the lever *m* in the opposite direction and the operation of the lock plates *h* will be reversed and the bar *c* will be moved to the right and carry with it the switch tongues *b*³ and *a*² and the switch will be again closed.

The operation of the lock plates *h* and of the lock links *f* and the bar *c* is facilitated by the anti-friction rollers *f*³ mounted in said lock links, and this operation depends on, or is the result of, the beveling of the outer corners of the inner end portions of said lock plates, whereby said lock plates are made wedge-shaped in form, or approximately so at their inner ends, and the positive lock of my improved apparatus depends upon the fact that the outer end portions of the lock plates *h* are rectangular in form and the opposite sides thereof parallel, this feature of the construction extending for approximately half of the length of said lock plates, and when either of the lock plates is in operation, neither the bar *c* nor the switch tongues can be moved except by the operation of the cross rod *k*, as hereinbefore described.

It must also be understood that, in practice, the lock boxes *d* and the parts mounted therein and connected therewith may be, and are preferably inclosed, and this may also be true of all the operative parts of my improved switch apparatus with the exception of the switch tongues *b*³ and *a*², and my invention is not limited to the use of the lever *m* for operating my improved switch apparatus, and said apparatus may be operated from a switch tower in the usual manner, and by any preferred means, and various changes in and modifications of the details of construction herein shown and described, may be made, within the scope of the appended claims, without departing from the spirit of my invention or sacrificing its advantages.

My invention is also not limited to the use of two switch tongues, nor to the arrange-

ment of main and switch rails herein shown and described, and the improvement which forms the basis of my invention may be applied to switches of any kind.

55

Having fully described my invention, what I claim as new and desire to secure by Letters Patent, is:—

1. A railway switch apparatus involving the usual rails and switch tongues, a cross bar with which said switch tongues are connected, lock link members connected with the opposite ends of said cross bar, and lock plate members movable through said lock link members, and means for operating said lock plate members in opposite directions.

2. In a railway switch apparatus, the combination with the usual switch tongues of a cross bar placed beneath the rails and said switch tongues and connected with said switch tongues, lock link members connected with the opposite ends of said bar, lock plates movable through said lock link members, and means for operating said lock plate members alternately in opposite directions.

3. In a railway switch apparatus, a cross bar mounted beneath the rails and movable transversely thereof, lock links mounted in connection with the ends of said bar, locking devices movable transversely through said lock links, and means for alternately operating said locking devices in opposite direction and for locking said bar in different positions.

4. A railway switch apparatus involving the usual rails and switch tongues, a cross bar with which said switch tongues are connected, lock members connected with the opposite ends of said cross bars, lock devices movable transversely of and in operative connection with said lock members, and means for alternately operating said lock devices in opposite directions and for locking said bar in different positions.

In testimony that I claim the foregoing as my invention I have signed my name in presence of the subscribing witnesses this 30th day of December, 1915.

JOHN C. BRINK.
